UNITED STATES PATENT OFFICE.

ISAAC FORBES GARNER AND WILLIAM B. HILL, OF CARTHAGE, MISSOURI.

LIMEKILN.

SPECIFICATION forming part of Letters Patent No. 338,056, dated March 16, 1886.

Application filed October 22, 1885. Serial No. 180,638. (No model.)

To all whom it may concern:

Be it known that we, ISAAC FORBES GARNER and WILLIAM B. HILL, citizens of the United States, residing at Carthage, in the 5 county of Jasper and State of Missouri, have invented certain new and useful Improvements in Limekilns; and we do declare the following to be a full, clear, and exact description of the invention, such as will enable 10 others skilled in the art to which it appertains to make and use the same, reference being had to the accompanying drawings, and to the letters and figures of reference marked thereon, which form a part of this specification. 15

Figure I is a transverse vertical section of the device through the furnaces. Fig. II is a similar section at right angles to that shown in Fig. I. Fig. III is a rear view of the kiln. 20 Fig. IV is a section, looking down on the grate-bars. Fig. V is a bottom view. Fig. VI is a front view of the doors. Figs. VII, VIII, and IX are detail views.

This invention relates to improvements in 25 limekilns; and it consists in the construction hereinafter set forth and claimed.

In the annexed drawings, the letter A indicates the kiln, consisting of the base B and input C, the latter having the fire-brick lining f. At the front and rear two furnaces, E E, are located in the base B, having the fire-boxes e e, the ash-pit e' e', and the fire-entrances e' e' through the kiln-walls. The openings to the furnaces have ways or guides 30 a a for sliding furnace-doors, and the pits have the usual doors, a' a'. On each side of the furnace-doors, and below them, are made air-flues c c'. These flues pass through the base of the kiln and enter the furnaces above 35 and below the fire-box, as seen in Fig. I. These flues are closed on the outside by suitable sliding doors or dampers. The bottoms of the fire-boxes have a slight flare upward at b b, which narrows the entrances e' e', and 40 above such flares are located in the top of the furnaces the cross-passages b' b'. The input C of the kiln increases in taper downward to the bottom of the entrances e' e'. Just below this point the taper ceases, and an enlarged 45 chamber is formed in the base of the kiln. This chamber F has its sides f at right angles

to each other and a flaring bottom. The four sides of the bottom converge toward the center with a downward flare, forming a chute. Three of the sides of the bottom are formed 55 of the base of the kiln, and the fourth of metal, there being an opening, f', where they terminate at the bottom. The side f' comes to the middle line of the kiln, (see Fig. II) at which point is placed a metal bar, f'', and 60 from which the wall f' drops vertically. Opposite the side f' is the metal side G. Metal plates g, with strengthening-ribs g', are placed with their lower ends, g'', resting on the bar f'', and their lengths supported on transverse 65 rods h, secured in the kiln. On these plates g are placed strips h' of sheet metal, side by side, leaving the opening f' at the bottom. To the under side of the plates g are secured rabbeted plates or guides k, which hold the 70 ends k' of a slide, K. This slide K closes the opening f', and is withdrawn by chain l, working over pulleys l'. From the vertical wall f' there is a diverging opening or recess, L, under the side G. This side G is prefer- 75 ably lined with fire-brick, as shown in the drawings.

The rock is put into the kiln at the top, and passes down. At the fire-openings e' it comes in contact with the products of combustion from the furnaces, and, being converted into lime, passes still downward and is withdrawn at the opening f' into a cart or other receptacle introduced at the opening L. Air is admitted to the fire, either below 80 through the flues c', or above through the flues c, and these can be regulated to throw it at different points, as the flues are independent of one another. The air entering the flues c' passes up through the fire, increasing the same. The air entering the flues c comes in contact with the flame above the fuel, and passing with the flame into the chambers b' induces better combustion. This action is facilitated by the flares b, which are 85 under the chambers b'.

Having thus described our invention, what we claim is—

1. A limekiln having the air-flues c c' above and below the fire-box, and the chamber b' above such box, as set forth.
2. A limekiln having the air-flues c c'

above and below the fire-box, the chamber b' above such box, and the flare b below the chamber, as set forth.

3. A limekiln having a converging bottom, one of the sides of the latter consisting of the plates g , cross-rods h , and strips h' , there being an opening, f' , at the bottom of such side, as set forth.

4. A lime-kiln one of the sides of the bot-

tom consisting of metal, with a fire-brick lining, as set forth.

In testimony whereof we affix our signatures in presence of two witnesses.

ISAAC FORBES GARNER.
WILLIAM B. HILL.
